United States Patent Office.

M. SULZBACHER, OF NEW YORK, N. Y.

Letters Patent No. 100,464, dated March 1, 1870.

IMPROVED SOFA-BEDSTEAD.

The Schedule referred to in these Letters Patent and making part of the same.

To all whom it may concern:

Be it known that I, M. SULZBACHER, of the city, county, and State of New York, have invented a new and improved Sofa-Bedstead; and I do hereby declare the following to be a full, clear, and exact description thereof, which will enable those skilled in the art to make and use the same, reference being had to the accompanying drawing forming part of this specification, in which drawing—

Figure 1 represents a transverse section of this invention when closed up to be used as a sofa.

Figure 2 is a similar section of the same when drawn out to be used as a bedstead.

Figure 3 is a sectional plan of the same.

Similar letters indicate corresponding parts.

This invention consists in a sofa having a sliding seat and a hinged piece which forms an auxiliary back to the main frame, and swings down in line with the seat, so that the sofa may be transferred into a bedstead. By folding up the hinged piece and sliding in the seat, the sofa is restored to its original position and use.

In the drawing, the letter A designates the frame of my sofa, which is constructed in the usual form.

In each of the end pieces a of this frame is secured a metallic lug, b, which catches in a groove, c, in the end piece of a secondary frame, B, that supports the seat C.

This secondary frame rests on casters, d, and it can

be readily drawn out to the position shown in figs. 2 and 3, the lugs b forming the guides on which it slides, and also the stops which prevent said frame being drawn out beyond the desired point.

D is an auxiliary back, which swings on gudgeons, e, whose bearings are in the end pieces of the main frame, so that it can be turned up to the position shown in fig. 1, or down to the position shown in figs. 2 and 3.

The front face of the back D may be upholstered or cushioned, or said back may consist of a cushioned frame.

In the bottom part of the main frame A is a receptacle, E, for the pillows, bed-clothes, &c.

By these means a sofa is obtained which can be readily transformed into a bedstead, and which is cheap and simple in its construction, no extra cushion being required in forming the bedstead.

What I claim as new, and desire to secure by Letters Patent, is—

The auxiliary back D, hinged to the end pieces a of the open frame A, in combination with the extension-frame B, sliding on lugs b, and disconnected from said end pieces, the parts operating together as and for the purpose described.

M. SULZBACHER.
